Specification of Letters Patent.

Patented May 9, 1916.

Application filed July 30, 1913. Serial No. 781,986.

To all whom it may concern:

Be it known that I, CHARLES H. CLARK, a citizen of the United States, and resident of Crafton, in the county of Allegheny and State of Pennsylvania, have invented certain new and useful Improvements in Tilting Side-Dump Cars, of which the following is a specification.

This invention relates to certain improvements in the tilting side dump car patented by me October 31, 1911, No. 1,007,533, and has particular reference to the provision of improved and highly efficient means for tilting the car body, also improved body-holding and releasing means.

One object is to provide two body-tilting mechanisms—one adapted to be operated at the car and the other from the locomotive or other available point, whereby the cars of a train may be dumped individually, or all the cars may be dumped simultaneously. Similarly, the latch mechanisms of the cars of a train may be operated either separately or collectively, their unitary operation being accomplished preferably by the same force that dumps the cars. The individually operating dumping mechanisms are preferably actuated manually, and the same is true of the latch mechanisms when operated one car at a time. The unlatching and dumping means are preferably embodied in fluid-pressure mechanism which is connected to a train line supplied from the locomotive.

A further object is to so construct and arrange the two operating mechanisms that they may be used interchangeably, with either in readiness to augment the other in all positions of the car body, but with neither mechanism interfering with the operation of the other, whereby either or both mechanisms are always available for the dumping operation.

In the accompanying drawings, Figure 1 is a side elevation of a portion of a side dump car constructed in accordance with the invention, and Fig. 2 is a top plan, partly broken away, of a portion of such car. Figs. 3, 4 and 5 are vertical cross-sections taken on lines 3—3, 4—4, and 5—5, respectively, of Fig. 1, in Fig. 3 the car body and only a portion of the operating mechanism being shown in dumping position in dotted lines, and in Fig. 5 all of the illustrated parts are shown in such position; also in Fig. 3 a por-

tion of the bolster diaphragm and other parts that would obstruct a view of the latch operating cylinder are omitted. Fig. 6 is a vertical central section of one end of the car body and one of the fixed end frames, together with mechanism associated with said parts, said view being taken on line 6—6 of Fig. 3. Fig. 7 is a vertical section of the fluid-pressure actuated latch-operating mechanism.

Referring to the drawings, 2 designates the longitudinal center sills of the car underframe, and supported at each end of the latter is an upright transverse frame 3, of which 4 is the wall-forming diaphragm. The car body 5 is supported adjacent each end by a transverse bolster 6 with the central portion of the bolster enlarged downwardly and curved to form the toothed rocker 7 which meshes with and is adapted to roll on the horizontal rack 8. The load-carrying portion of the body consists of the normally horizontal floor 9, fixed end walls 10, and downwardly and outwardly opening longitudinal side walls or doors 11, one of the latter forming a downward and outward extension at the dumping side of the car when the body is inclined, as shown at the left hand of Fig. 5. Duplicate body-holding latch-mechanisms are preferably provided at each side of each rocker, as shown in Fig. 1. Extending longitudinally through the underframe at the outer sides of girders 2 are shafts 12 to which are secured the hook-like latch heads 13. Shafts 12 extend to opposite ends of the car, and secured thereto are the hand levers 14 which extend upwardly through platform 15. Cooperating with each latch head 13 is an arm 16 pivoted at its upper end to bolster 6, the lower portion of the arm being slotted at 16' where it embraces pin 17 carried by the guide link 18, said link being pivoted to and depending from the underframe and adapted to direct pin 17 into and out of position for engaging latch head 13. As shafts 12 extend from end to end of the car, all of latch heads 13 at one side or the other may be manually released by operating the appropriate lever 14 at either end. When dumped by manual power the latches at the unreleased side remain in holding position, preventing the body from tilting in the wrong direction, but without interfering with the

dumping operation, arms 16 of the unreleased latch devices simply moving downwardly over the latch-held pins 17, as will be understood.

- 5 The mechanical power means for releasing the latches is preferably embodied in fluid-pressure mechanism which consists of a cylinder 19 which may be secured to one of girders 2, with the lower extremity of 10 stem 21 of piston 20 bifurcated at 22 to embrace pin 23 of bell-crank 24, the latter fulcrumed in bracket 25 secured to the undersides of the girders 2. Extending in opposite directions from the bell-crank are arms 15 26, each slotted at its outer end at 26' to embrace a pin 27' at the lower extremity of arm 27 on shaft 12. Normally, the inner ends of slots 26' engage pins 27', as in Fig. 3, so that when air or other pressure fluid 20 is admitted to cylinder 19 the lowering of piston 20 shifts bell-crank 24 and arms 26 into the position shown in Fig. 5, releasing all the latch heads 13 from pins 17, the mechanical power mechanism operating to 25 release the latch heads at both sides so that the car body is free to dump toward either side of the track. The air pressure may be maintained as long as it is desired to hold the body in dumping position, during which 30 time hand levers 14 are upwardly tilted as shown in Fig. 5. But as soon as the air is released the levers drop by gravity to the position shown in Fig. 3, returning the latch heads 13 to position to be automatically 35 engaged by pins 17 when the body rocks back to horizontal position as in Fig. 4. Similarly, when manually operated the latch heads remain in unlocked position only so long as one of the levers 14 is held 40 raised, the lever upon being released dropping to normal position and returning the latch heads to holding position.

The mechanism for tilting the car body and for controlling it throughout its tilting 45 movement will now be described.

Secured to and projecting outwardly from the opposite end walls 10 of the body are the bearing-forming trunnions 30 which are located at the center of rocking of the body, 50 and hence movable horizontally as the body rocks. Journaled on each trunnion 30 is pinion 31, Figs. 3 and 6, which meshes with transverse horizontal rack 32 at the under side of the top chord of end frame 3. Journaled in the tilting body and extending therethrough from end to end beneath floor 9 is shaft 33, and interposed at each end of the car body between shaft 33 and pinion 31 is a train of reducing gearing, the ends 55 of the train being mounted on trunnion 30 and shaft 33, the intermediate portion of the train being mounted on journal 34 projecting from the end of the car body. Gear wheel 35 of the train mounted on trunnion 30 is secured to pinion 31 by hub 36. Thus

it will be seen that the mechanisms at the opposite ends of the car body are so connected that said ends must move in unison and that movement communicated to one end of the body is directly transmitted to the other end. 70

Force for dumping the car may be applied by either of two means which may be operated interchangeably, neither interfering with the other. One mechanism is operated 75 at the car for dumping each car individually, being preferably embodied in manual-power means. The other mechanism is actuated by mechanical power means, preferably by air pressure derived from a train 80 line to which air is admitted for dumping a number of cars of a train simultaneously. For the manual operation, hand wheels 37 are secured to the ends of shaft 33 so that the body may be dumped from either end, 85 the interposed trains of gearing constituting winches of such power that the operation may be readily performed by hand. When operated by hand the appropriate lever 14 is thrown to release the latches which hold 90 that portion of the car which is to rise in the tilting movement, and then one of the hand wheels 37 is rotated as required for tilting the body. The fluid-pressure tilting operation is accomplished by means of cylinders 95 40 located at either end of the body, each having one end thereof pivotally connected at 41 to head 42 which embraces the top chord of end frame 3 and which, together with cylinder 40, is slidable horizontally 100 thereon. At the inner side of head 42 is a depending bifurcated extension 43 which embraces gear hub 36, Figs. 6 and 3. Rod 45 of piston 44 extends through the outer end of cylinder 40 and is adapted to seat in 105 notch 46' of one or the other of two abutments 46 secured to frame 3. Bearing 41 and the head cylinder 40 are ported at 47 to admit air or other pressure-fluid to the cylinder, and when so-admitted the cylinder is 110 caused to move horizontally, as shown in Fig. 5 and in dotted lines in Fig. 3, piston 44 being held fixed by abutment 46, as will be understood. As trunnions 30 and gear hubs 36 are embraced by the bifurcated portions 43 of heads 42, they must travel therewith, and hence tilting force is imparted to the car body. And as said trunnions are 115 geared to the fixed frame ends by pinions 31 and racks 32, and as the gear mechanisms at opposite ends of the car are connected by shaft 33, the same force and the same movement is imparted to each end of the body.

Cylinders 40 may be turned on their pivots 41 to extend toward either side of the 125 car, determined by the direction in which the body is to tilt. Thus, if the load is to be dumped at the lefthand side, as in Fig. 3, the cylinder is projected toward the righthand side of the car, while if the body is to 130

be dumped at the righthand side the cylinder is thrown over or in a reverse position from that shown in Fig. 3.

When operating with compressed air a desirable arrangement is such that the air is first admitted to cylinder 19 for unlatching the body and is then passed on to cylinders 40 at opposite ends of the car after the latch mechanism has been operated. This may be conveniently accomplished by connecting the dump operating train line 50 with the upper end of cylinder 19, as indicated at 51, and extending a pipe 52 in opposite directions from cylinder 19 to bearing 41, a portion of the length of each end of said pipe being flexible, as indicated at 52', to compensate for the horizontal movement of cylinders 40. Thus, when the air is admitted to train line 50 for dumping one or any desired number of cars, it first depresses the latch-operating piston 20 of each car and releases the latches, as shown in Fig. 5, and as piston 20 moves downward it uncovers pipe connection 52 and admits the air to cylinders 40 which results in tilting the car body toward one side or the other, determined by the position of the cylinders.

It is characteristic of the invention that each of the dumping mechanisms is operative in all positions of the body, so that either mechanism may supplement or supersede the other whenever necessary.

In the present adaptation, as in that of my above mentioned patent, the center of gravity of the loaded body lowers during the tilting movement and facilitates the dumping operation. At the same time the center of gravity of the car body itself rises, so that when entirely empty the tendency of the body is to rock back to upright or horizontal position, thus automatically righting itself upon the release of the fluid pressure, and automatically relatching. Wood or other buffer or cushioning devices 53 may be arranged on the underframe for checking and limiting the tilting movement, being engaged by the body when fully tilted, as shown in Fig. 5.

Each of the side doors 11 is hinged at 55 beneath floor 9 and is adapted to swing downwardly and outwardly, forming a chute-like extension which discharges the lading away from the track. The opposite doors are connected by the floating bar 56 and links 57, said bar being movable in a double guide 58 having the opposite upstanding curved faces 59 which control or direct the movement of the bar through the medium of rollers 60 at opposite sides of the latter and engaging said curved faces. The doors are operated by the connecting mechanism as described in my above mentioned patent, the door at the dumping side of the body automatically opening as that side lowers, and automatically closing as

the body returns to upright position. The connecting mechanism holds the doors closed when the body is in erect position, and similarly holds the inactive door during the dumping operation.

Claims for the manually-operated body-tilting mechanism herein shown and described are made in an application for patent filed by me concurrently herewith.

I claim:

1. In a dump car, the combination of a frame, a body mounted to tilt on the frame in opposite directions for dumping at either side of the car, latch devices for the body located at opposite sides of the longitudinal center of the car, fluid pressure actuated means connected to the latch devices for releasing them, and reversibly mounted body tilting means for tilting the body toward either side.

2. In a dump car, the combination of a frame, a body mounted thereon to tilt toward either side of the car, latch devices located at opposite sides of the longitudinal center of the car for holding the body erect, means for releasing the latch devices simultaneously, and means for controlling the direction of tilting of the released body.

3. In a dump car, the combination of a frame, a body mounted to tilt thereon toward either side of the car, latch devices at opposite sides of the longitudinal center of the body for holding the latter erect, a power cylinder and piston and an operative connection between the latter and the latches for releasing the latches simultaneously, and means for controlling the direction of tilting of the released body.

4. In a dump car, the combination of a car body mounted to tilt toward either side for dumping, latch devices for holding the body against tilting in one direction and other latch devices for holding the body against tilting in the opposite direction, means for simultaneously moving all of the latch devices to body releasing position, and means for controlling the direction of tilting of the body.

5. In a dump car, the combination of a car body mounted to tilt toward either side for dumping, latch devices for holding the body against tilting in one direction and other latch devices for holding the body against tilting in the opposite direction, manual means and mechanical-power means operative interchangeably for simultaneously moving all of the latch devices to body-releasing position, and means for controlling the direction of tilting of the body.

6. In a dump car, the combination of a frame, a body mounted to tilt thereon for dumping at opposite sides of the car, longitudinally slotted arms pivoted to and depending from the body, guide links—one

- for each arm—pivoted to the frame and adjustably connected to said arms by means of the slots in the latter, and latch devices on the frame adapted to operatively connect 5 with said arms.
7. In a dump car, the combination of a frame, a body mounted to tilt thereon toward either side of the car, shafts located at opposite sides of the center of the frame 10 and extending from end to end of the latter, fluid pressure-actuated means located adjacent opposite ends of the frame and operatively connected to said shafts, and body-holding latches mounted on the shafts and 15 adapted to be moved by the latter into body-releasing position.
8. In a dump car, the combination of a frame, a body mounted to tilt on the frame, a fluid-pressure cylinder supported by the 20 frame and pivotally connected to the body and adapted to be rotated about said pivotal connection and thereby extended toward either side of the car, a piston and piston rod, and piston rod holders located on the 25 frame for confining the rod in either position of the cylinder.
9. In a dump car, the combination of a frame, a body mounted to tilt on the frame, a device supported by and movable on the 30 frame transversely of the car and operatively connected to the body for tilting the latter, and a power cylinder and piston pivotally connected to said device and supported by the frame and adapted to be 35 turned to reverse positions about said pivotal connection for tilting the body toward either side of the car.
10. In a dump car, the combination of a frame, a body mounted to rock on the frame, 40 a device supported by and movable on the frame transversely of the car, a projection on the body with the projection engaged by said movable device, and a power cylinder and piston pivotally connected to said device and supported by the frame and adapted to be turned to reverse positions about 45 said pivotal connection for rocking the body toward either side of the car.
11. In a dump car, the combination of a frame, a body mounted to rock on the frame, 50 a device movable on the frame transversely of the car, a projection on the body engaged by said movable device, a power cylinder movable on the frame and pivotally connected to said movable device, the position 55 of the cylinder being reversible about said pivotal connection for rocking the body to- ward either side of the car, a piston and piston rod, and piston rod holders on the frame for confining the rod in either position of the cylinder. 60
12. In a dump car, the combination of a car body mounted to tilt toward either side for dumping, latch devices for holding the body against tilting, and manual means and 65 mechanical-power means operative interchangeably for actuating the latch devices.
13. In a dump car, the combination of a frame, a body mounted to tilt thereon for dumping at opposite sides of the car, latch 70 devices movably mounted in the frame, means carried by the body at opposite sides of its center adapted to be engaged and released by the latch devices, and manual means and mechanical-power means connected to the said latches and operative interchangeably for releasing the same. 75
14. In a dump car, the combination of a frame, a body mounted to tilt thereon for dumping at opposite sides of the car, depending longitudinally slotted arms pivotally connected to the body at opposite sides of its center, guide links pivoted to the frame, pins carried by the guide links and projecting through the arm slots, latches 80 connected to engage the pins, and latch-operating means. 85
15. In a dump car, the combination of a frame, a body mounted on the frame to tilt toward either side of the car, latch devices for holding the body erect, a bell-crank operatively connected to the latches for operating them simultaneously, bell-crank operating means, and body-tilting means controllably connected to the latch-operating means. 90
16. In a dump car, the combination of a frame, a body mounted on the frame to tilt toward either side of the car, latch devices adapted to releasably connect with the body 10 at opposite sides of the center of the latter, a bell-crank fulcrumed to the frame, operative connections between the bell-crank and the latch mechanisms, and a power cylinder and piston with the piston operatively connected to the bell-crank for moving the latter to simultaneously release the latch mechanisms. 105
